(57) **CLAIM**

The ornamental design for a double sided wall tap, as shown and described.

DESCRIPTION

FIG. 1 presents a pictorial view of my new double sided wall tap design.

FIG. 2 presents a front elevational view of the double sided wall tap as illustrated in FIG. 1.

FIG. 3 presents a right side elevational view of the double sided wall tap illustrated in FIG. 1.

FIG. 4 presents a rear elevational view of the double sided wall tap illustrated in FIG. 1.

FIG. 5 presents a left side elevational view of the double sided wall tap illustrated in FIG. 1.

FIG. 6 presents a bottom view of the double sided wall tap illustrated in FIG. 1; and,

FIG. 7 presents a top view of the double sided wall tap illustrated in FIG. 1.

The broken lines in the drawings are for illustrative purposes only and form no part of the claimed design.
